UNITED STATES PATENT OFFICE.

WILLIAM M. ESTES, JOHN F. ESTES, AND JESSE H. SMITH, OF CULLMAN, ALABAMA.

CULTIVATOR ATTACHMENT.

No. 887,078.

Specification of Letters Patent.

Patented May 12, 1908.

Application filed January 10, 1908. Serial No. 410,174.

To all whom it may concern:

Be it known that we, WILLIAM M. ESTES, JOHN F. ESTES, and JESSE H. SMITH, citizens of the United States, residing at Cullman, in 5 the county of Cullman and State of Alabama, have invented a new and useful Cultivator Attachment, of which the following is a specification.

This invention has relation to fender attachments for cultivators and it consists in 10 the novel construction and arrangement of its parts as hereinafter shown and described.

The object of the invention is to provide 15 an attachment of the character indicated which may be easily and readily applied to the beam of a cultivator and adjusted thereon and which is so constructed as to effectually ward off the earth cast up by the cultivator shovels and protect the standing plants 20 from the same.

The fender consists of discus members 25 mounted upon arms and which are adapted to move along the opposite sides of a row of plants, said arms being pivotally mounted and adapted to swing vertically and independently of each other so that the disks may ride over obstructions and coöperate in keeping each other free of trash and the like. The 30 said arms are attached to ogee shaped sides of a yoke which in turn is adapted to engage the cultivator beam as above indicated.

Figure 1 is a side elevation of the attachment applied to a beam, and Fig. 2 is a perspective view of the attachment with parts 35 removed and parts in section.

The attachment consists of the yoke 1 which is provided with the parallel spaced ogee side portions 2, 2. The intermediate portion of the yoke 1 is adapted to lie under 40 the beam of the cultivator bracket (indicated by 3 in the drawing) and the intermediate portions of the ogee extremities 2 are connected together by a cross bolt 4 which passes through a perforation in the said cultivator beam. The rod 5 is located between the rear 45 ends of the portions 2 of the yoke 1 and is provided at its opposite ends with the clamp nuts 6 which are adapted to engage the outer sides of the said portions 2. The sleeve 7 is 50 mounted upon the rod 5 and bears at its ends against the inner sides of the portions 2. The

arms 9 are pivoted at their forward ends upon the rod 5 and are provided at the lower edges of their forward extremities with the inwardly disposed lugs 9 which are adapted to 55 lie under and engage the lower edges of the portions 2 of the yoke 1 whereby the pivotal movement of the arms 8 with relation to the said portions 2 is limited and when the said arms 8 are in their lowermost positions they 60 are substantially in alinement with the rear extremities of the portions 2 of the said yoke 1. The disks 10 are journaled upon the arms 8. The arms 8 are laterally bent at intermediate points as at 12 in order to properly 65 space the disks 10 apart.

From the foregoing description it is obvious that when the yoke 1 is placed upon a beam 3 so that its intermediate portion is under the beam and the bar 4 is over the beam 70 that the weight of the rear end portions of the said yoke and the arms and disks carried thereby will cause the intermediate portion of the said yoke to bind against the beam with sufficient intensity to maintain its ad- 75 justed position upon the beam without the aid of securing devices of a positive nature. When the yoke is so mounted and the disks 10 are moving along the opposite sides of the row of plants the said disks will protect the 80 standing plants from the earth cast up by the cultivator shovels. Furthermore, should either one of the said disks encounter an ob- 85 struction it will ride over the same without elevating the other disk and should either 90 one of the disks collect trash the other disk will elevate sooner or later by meeting an ob- struction and when it passes over the said 95 obstruction and descends it will be liable to encounter the trash collected about the first 100 said disk and free the disk of the trash. The advantage gained by having the contour of the members 10 circular or in the form of disks is that no angles are presented for the collection of trash or for tearing through the foliage of the standing plants. As the edges of the disks present nothing but obtund curves to obstructions, trash and the standing plants they tend to ride smoothly over the obstructions, minimize the collection of trash and avoid injury to the growing plants.

Having thus described our invention what

we claim as new and desire to secure by Letters-Patent is:

A fender comprising a yoke having ogee side portions connected together at intermediate points by a cross bolt which lies in a plane elevated with relation to the planes occupied by the end portions of the yoke, arms pivotally attached to the rear ends of the ogee portions of the yoke and fender members attached to said arms.

In testimony that we claim the foregoing as our own, we have hereto affixed our signatures in the presence of two witnesses.

WILLIAM M. ESTES.
JOHN F. ESTES.
JESSE H. SMITH.
